FIG. 1 is a front elevational view of a packaging container for a doll showing my new design.

FIG. 2 is a top plan view thereof.

FIG. 3 is a rear elevational view thereof, taken on line 3-3 of FIG. 2.

The bottom is substantially the same in appearance as the top.

The broken line showing of the doll in FIG. 1 is for illustrative purposes only.

I claim:

The ornamental design for a packaging container for a doll, as shown and described.
